CLAIM

The ornamental design for a pendant light as shown and described.

DESCRIPTION

FIG. 1 shows a front perspective view of a pendant light; FIG. 2 shows a front view of the pendant light of FIG. 1; FIG. 3 shows a rear view of the pendant light of FIG. 1; FIG. 4 shows a right side view of the pendant light of FIG. 1;

FIG. 5 shows a left side view of the pendant light of FIG. 1; FIG. 6 shows a top view of the pendant light of FIG. 1; and, FIG. 7 shows a bottom view of the pendant light of FIG. 1. The broken lines immediately adjacent to the shaded areas depict the bounds of the claimed design, while all other broken lines are directed to environment. The broken lines form no part of the claimed design. The “Nite Ize” lettering and icon forming part of the disclosure is a registered trademark of Nite Ize, Inc.
